UNITED STATES PATENT OFFICE.

HARRY S. BERLIN, OF SPRINGFIELD, OHIO, ASSIGNOR TO THE VICTOR RUBBER COMPANY, OF SPRINGFIELD, OHIO, A CORPORATION OF OHIO.

DESIGN FOR A PNEUMATIC-TIRE TREAD.

61,148.

Specification for Design.

Patented July 4, 1922.

Application filed October 8, 1921. Serial No. 506,526. Term of patent 14 years.

To all whom it may concern:

Be it known that I, HARRY S. BERLIN, a citizen of the United States, residing at Springfield, in the county of Clark and State of Ohio, have invented a new, original, and ornamental Design for Pneumatic-Tire Treads, of which the following is a specification, reference being had to the accompanying drawing, forming part thereof.

The figure is a perspective view of a portion of a pneumatic tire casing showing my new design.

I claim:

The ornamental design for a pneumatic tire tread, as shown.

HARRY S. BERLIN.
